ELECTRON STORAGE DEVICE

Max Knoll, Princeton, N. J., and Paul Rudnick, Fort Wayne, Ind., assignors, by mesne assignments, to the United States of America as represented by the Secretary of the Army

Application January 15, 1954, Serial No. 404,332

6 Claims. (Cl. 313—68)

This invention is directed to storage tubes and more particularly to the insulating material serving to store the electric charges that make up a stored image.

In general, a storage tube is an electron tube into which information can be introduced and then extracted at a later time. In a charge-controlled storage tube the information is retained by static electric charges. Such charges are generally retained on a homogeneous insulating surface, on an insulating coating over a conducting mesh, or on an array of discrete insulated areas for definite periods of time, as needed. It is desirable that the resistance of the storing material remain as high as possible even at higher temperatures.

The action of establishing a charge pattern corresponding to an input signal is known as writing. The retentive feature of this action may also be referred to as storing. Retention of the stored charge pattern for a period of time is accomplished by means of the insulating properties of the surface of a target electrode. In a viewing storage tube provision is made for the formation of a visible image corresponding to the pattern of stored charges.

The generation of an electrical or visual output signal corresponding to the stored charge pattern is known as reading. Erasing takes place by the removal of a previously stored charge pattern with the aid of some controllable process such as secondary emission or photoconductivity, and may be accomplished by the writing beam.

In certain types of storage tubes the storage insulator is located close to some major source of heat such as a large-area thermionic cathode. At the high temperatures there found, most insulating materials tend to lose their effectiveness in storing electric charges. In these cases increased temperature produces an exponential decrease of specific resistance of the material and the stored charges leak off.

It is therefore an object of this invention to provide an improved electronic device for the storage and visual presentation of information, in which the insulating material serving to store the information may be operated at high temperature and still be capable of retaining information for a useful length of time.

A further object of this invention is to provide for use in a storage tube an improved insulating material which can retain a stored charge for a longer period than can other storage material under changing ambient temperatures.

The objects of the invention may be realized through an embodiment which makes use of a polymerized surface film formed over a storage target electrode. The polymerized surface film may be formed directly over the conducting base of a target electrode or over the usual layer of magnesium fluoride, silica or other insulator used as the storage element in an electronic storage device. This film is of a hydrocarbon nature, polymerized, and is formed by electron bombardment of a target electrode in a suitable rarefied hydrocarbon atmosphere.

5

10

Referring to the drawing, a viewing type storage tube 10 is shown having an evacuated, substantially cylindrical envelope 20, for example, a glass bulb. Positioned within the cylindrical envelope 20 is a large thermionic cathode 21 held in place by an electrically conducting cathode support 22 and so disposed near one end of the envelope 20 as to be capable of emitting a wide viewing beam of electrons toward the other end of the envelope. Heater element 23 is positioned within the thermionic cathode 21 sufficiently close to the thermionic cathode 21 to heat it efficiently. The storage target electrode 24 is held in place adjacent to the thermionic cathode by electrically conducting target supports 25 and 26.

The storage target electrode 24 associated with this invention may be any of the usual types. Its surface may be homogeneous or meshed. The hole spacing of the mesh is determined by the amount of resolution desired. It may be made of woven wires or formed by etching or electroplating. The invention, however, will be more fully and easily understood from a detailed description of a single type of target surface and for this purpose an electro-formed mesh approximately .001 of an inch thick and with about 200 grid openings per linear inch has been chosen. Each cross-grid 30, in this embodiment of the target structure, is of such size as to form apertures 31 which are equal in combined area to approximately 50% of the total target surface.

The usual storage layer 32, which may be magnesium fluoride, silica or some other suitable insulator, is here shown formed over each cross-grid 30. For purposes of clarity, storage layer 32 thickness has been considerably exaggerated. According to this invention a polymerized hydrocarbon film 33 is deposited on the target electrode 24 over the usual storage layer 32.

The large viewing beam of electrons which is emitted by the thermionic cathode 21 during operation is focused magnetically by a field from a focusing coil 36 to impinge on the luminescent viewing screen 38, at the end of the cylindrical envelope 20 opposite to a thermionic cathode 21, through the grounded aluminum layer 39. The aluminum layer 39 lies directly over the luminescent viewing screen 38 and over a large part of the inner cylindrical surface of the envelope 20.

The writing gun 60 is placed within the neck 61 of the image storage tube 10 and so disposed as to be in a position to emit a beam of electrons 62 in the direction of the storage target electrode 24. The electron gun 60 comprises a cathode electrode 63, a control electrode 64, a first accelerating electrode 66, a focusing electrode 68, and a second accelerating electrode 69. The foregoing electrodes form the electron beam 62 emanating from the cathode 63 of the gun 60 into a sharply defined and focused beam. Separate pairs of deflection plates 72 and 74 are provided for electrostatically deflecting the beam in the desired manner.

The viewing storage tube shown in the drawing contains both an electronic storage system and elements which make the stored information visible for an appreciable time from outside the tube. During operation, the large thermionic cathode 21 emits electrons substantially uniformly over its whole surface in a large beam which is focused magnetically by the field from focusing coil 36 onto the luminescent viewing screen 38. In the absence of any modulation by the storage target electrode 24, the bombarded area of the screen is of uniform brightness.

During a writing cycle, with the thermionic cathode 21 switched to ground potential through the switch 76, as

the writing gun 60 scans the insulating film 33, it forms a pattern of charge or potential on the exposed surface of film 33 by any of the various known methods of modulation for storage tubes in which an incoming signal is fed to the control grid 64, as described in the book "Storage Tubes and Their Basic Principles" by Knoll and Kazan and published in 1952 by John Wiley and Sons. Suitable operating voltages are shown in the drawing. The storage target electrode may be set at a potential of zero to 100 volts depending upon the geometry of the particular tube. Then, during the reading part of the cycle, with the large thermionic cathode at -5,000 volts with respect to ground, in regions of film 33 left with a relatively high negative charge with respect to the thermionic cathode 21, the apertures 31 in the target electrode 24 will be closed to electrons from thermionic cathode 21 by the field from this high negative charge and will produce no luminescence on screen 38. In regions which are relatively highly positive, all available electrons from the thermionic cathode 21 will penetrate the apertures 31 in the target electrode 24 and will be focused on the luminescent viewing screen 38, giving highlights to the picture or other pattern of information. Regions at intermediate potentials will allow smaller electron currents from the thermionic cathode 21 to penetrate the target electrode 24 and bombard the luminescent viewing screen 38, yielding half-tones. Thus the incoming electrical signal is converted into a visible picture containing desired information, which will persist until the next writing cycle leaves a different pattern on the insulating film 33. The new and important feature of this device is the polymerized hydrocarbon film 33 which makes possible the storage of charge or potential patterns on an insulator in relatively close proximity to the hot cathode, as required in a storage tube of this type. It also makes possible other advantages which will be described

Glass side tubes 77 and 78 are employed only during the process of forming the polymerized layer 33 over the target electrode 24 and are sealed off close to the envelope 20 before actual operation of the viewing storage tube 10. A few drops of oil 80, preferably of low vacuum pressure (Octoil, for example) such as is used in oil diffusion vacuum pumps, are left deposited in the glass bottle 79 the opening to which is controlled by valve-stopper 81.

Polymerization of a hydrocarbon film over a storage target electrode may conveniently be accomplished at room temperature. The storage target electrode is so disposed within the evacuated envelope of a storage tube as to facilitate bombardment by an electron gun. An oil diffusion pump is continuously operated to maintain a pressure of 10^{-5} mm. of mercury. If an electron gun, similar to the writing gun 60 in the neck of the image storage tube 10 is chosen, it is operated at the voltages shown in Figure 1 except for the control grid which is maintained at -5000 volts. Under these conditions an unfocused electron beam of approximately 1 milliampere will be swept across the surface of the storage target electrode. A polymerized hydrocarbon film 0.1 micron thick would be formed over a storage target electrode approximately 3 cm. in diameter in approximately 24 hours or less depending on the residual gas pressure within the tube. The use of an inexpensive electron spray gun which is capable of emitting an unfocused beam of 100 milliamperes reduces the time of formation of the film to approximately 15 minutes. In the region of the values here used the rate of growth of the film is substantially linear with beam current intensity.

For practical purposes a storage layer of the thickness of 0.1 to 10.0 microns has been found effective. In general, for storage tubes layers of a thickness of 0.1 to 100 microns are used.

If an oil diffusion pump is used for the purpose of evacuating the glass envelope sufficient oil vapor is present in the atmosphere of the partially evacuated envelope for the formation of the polymerized hydrocarbon film. Where a mercury diffusion pump is used it may become necessary to introduce some oil vapor through the side tube 78 connected to the bottle 79 into which has been deposited a few drops of some oil of low vacuum pressure.

- 10 The polymerized film may be formed either over the surface of some other insulating layer such as silica or magnesium fluoride; or it may equally effectively be formed directly on the bare conducting base of the storage target electrode.

15 Similarly, the polymerized hydrocarbon film may be formed over the storage target electrode within a bell jar. If done in this manner the same conditions prevail as would prevail under those circumstances where the film is formed in the envelope of the storage tube.

20 An electron gun is required and is so disposed and activated that it can bombard a storage target electrode with a beam of adequate current intensity. Care must be taken however in removing the target electrode from the bell jar to prevent contamination.

25 Thus, by electron bombardment within a suitable atmosphere containing small amounts of oil vapor, a hydrocarbon film will be polymerized upon the surface of a storage target electrode making it a highly effective insulator for storage purposes.

30 The hydrocarbon film may be used as a storage element in all kinds of charge controlled storage tubes and its use is not limited to the storage tube 10 described in the drawing herein. The use of the hydrocarbon film as a storage element carries with it other definite advantages. Storage tubes with a higher degree of vacuum can thus be produced. The higher temperature required for processing of such tubes does not disintegrate the hydrocarbon film. Other insulating storage materials frequently are evaporated in such processes.

35 Also, images may be stored for long periods of time under high temperature. Furthermore, with the storage grid at 220° C. the retention time of a polymerized film has been observed to be ten times longer than that of uncoated silica at the same temperature. Television projection storage tubes of the transmission control type could be made to yield brighter images as neither the higher voltages nor the higher temperatures there required would lower the effectiveness of the polymerized hydrocarbon storage element.

40 What is claimed is:

1. An electron storage device comprising an electron gun for producing a beam of electrons along a path, an electrically conductive target electrode mounted transversely of said path, a layer of insulating material on said target electrode, and a polymerized film formed on the said layer of insulating material.

45 2. An electron storage device comprising an electron gun for producing a beam of electrons along a path, an electrically conductive target electrode mounted transversely of said path, a layer of insulating material on said target, and a polymerized hydrocarbon film formed on the said layer of insulating material.

50 3. An electron storage device comprising an electron gun for producing a beam of electrons along a path, an electrically conductive target electrode mounted transversely of said path, a layer of insulating material on said target and facing said gun, and a polymerized hydrocarbon film formed on the said layer of insulating material.

55 4. An electron storage device comprising an evacuated envelope, an electron gun within said envelope for the production of a beam of electrons along said path, an electrically conductive target electrode mounted within said envelope transversely to the said path, an insulating

coating on the surface of said target electrode, and a polymerized film formed on said insulating coating.

5. An electron storage tube comprising an evacuated envelope, an electron gun within the said envelope for the production of a beam of electrons along a path, a meshed electrically conductive target electrode mounted within said envelope transversely to the said path, and a polymerized hydrocarbon film on said meshed target electrode.

6. A target electrode, for an electron storage device, comprising an electrically conductive target base, a layer 10 of insulating material on said electrically conductive target base and a polymerized hydrocarbon film on said layer of insulating material.
